United States Patent Office

Des. 210,419
Patented Mar. 5, 1968

210,419

PAIR OF SPECTACLES

Jack Bloch, Leominster, and Vitalino Marchi, Concord, Mass., assignors to Foster Grant Co., Inc., Leominster, Mass., a corporation of Delaware

Filed Dec. 30, 1966, Ser. No. 5,231

Term of patent 14 years

(Cl. D57—1)

FIG.1

The drawing is shaded to indicate contrast.

We claim:

The ornamental design for a pair of spectacles, substantially as shown and described.
